UNITED STATES PATENT OFFICE.

CHARLES F. WALLACE, OF TOMPKINSVILLE, AND MARTIN F. TIERNAN, OF JAMAICA,
NEW YORK.

VALVE.

1,305,182.

Specification of Letters Patent.

Patented May 27, 1919.

Application filed May 4, 1918. Serial No. 232,633.

To all whom it may concern:

Be it known that we, CHARLES F. WALLACE and MARTIN F. TIERNAN, citizens of the United States, residing at Tompkinsville, borough of Richmond, county of Richmond, and State of New York, and Jamaica, county of Queens, and State of New York, respectively, have invented certain new and useful Improvements in Valves, of which the following is a full, clear, and exact description.

The invention subject of this application for Letters Patent is an improvement in valves, more especially of that class or kind which are used for controlling the flow of gases or fluids under high pressure, for which purpose, as is well known, a very minute movement of the valve stem and the sure maintenance of the valve in the position to which it has been thus brought are essential, and it is distinguished by the presence of a valve stem movable from or toward its seat by means of a threaded member with which the said stem engages, which member is in turn in threaded engagement with the body of the valve and constitutes a protective covering—the two threads by which the said member engages the valve stem and the outside of the valve body respectively being both in the same direction but of different pitch, the thread by which said member engages the valve body being of greater pitch than the thread by which it engages the valve stem, thus producing a slow differential movement of the valve to and from its seat.

This improvement in actual use has been demonstrated to be of the highest practical value. It constitutes a very perfect and durable means of control, with no parts subject to appreciable deterioration from wear, its construction is extremely simple and the number of parts comprising it is an irreducible minimum.

The invention is illustrated in the accompanying drawing in which—

Figure 1 is a vertical central section of the complete device; and

Fig. 2 is a top plan view of the same.

The numeral 2 designates the valve body designed or adapted to be joined to a pipe or conduit carrying a gas or fluid under pressure. 3 is the valve seat and 4 is a branch outlet integral with or in any proper manner secured to the body.

5. The valve stem is properly fashioned to

fit the seat and extends upward through a collar 6, a packing 7 and a packing gland 7' into the internally threaded cap 8 with which it engages.

The valve body is externally threaded for engagement with the cap, and internally threaded for the packing gland which after the stem has been inserted is screwed down to form a perfectly tight fitting joint therewith.

When these parts have been put in place the cap 8 is screwed down on the end of the valve body 2 and the projecting end of the stem until the parts assume the relations shown in Fig. 1 with the valve stem forced tightly down on its seat. The cap 8 has wings 9 by which it may be turned and when it is unscrewed it will raise the stem up from its seat, or when turned in the opposite direction it will force the stem down upon its seat by reason of the fact that the threads between the cap and the valve body are of greater pitch than those between the cap and the valve stem. In either case the stem is prevented by friction with the gland and packing from rotating, and merely moves axially through the packing.

The frictional resistance to the stem turning is all that is required in practice to prevent its rotation, and no other means need be employed for the purpose unless so desired. The invention, moreover, is not limited to the specific arrangement of threads, as it is only necessary that there should be a differential threaded engagement of the character described between the stem and the cap and between the latter and the valve body or other stationary part to secure the results herein set forth.

What we claim is:

1. A valve comprising an externally threaded valve body; a valve seat therein; a stem axially movable to and from the seat and having an external thread in the same direction as, but of less pitch than, that on the exterior of the valve body; and an internally threaded cap, engaging the externally threaded valve body and constituting a protective cap therefor, and containing an internally threaded socket to receive and engage the externally threaded stem.
2. A valve comprising a seat and an axially movable stem, a packing through which the stem passes, a cap with which it has threaded engagement, and a valve body with

which the cap has threaded engagement, the threads between the cap and the valve body being of greater pitch than those between the cap and the valve stem, whereby by turning the cap the stem will be raised or lowered with reference to its seat, but prevented by friction from being rotated.

3. A valve comprising a seat, a packing and an axially movable stem passing through the packing, a cap with an internally threaded part for engaging with the free end of the stem and with another internally screw-threaded part to screw onto the valve body, the threads between the cap and the valve body being of greater pitch than those between the cap and the valve stem, whereby the turning of the cap will

raise or lower the stem with reference to its seat without rotating it.

4. A valve comprising a body, a seat and an axially movable stem, a packing through which the stem passes, a gland engaging with threads on the valve body and adapted to be screwed down on the packing, a cap with an internally threaded screw for engaging with the stem and a threaded portion engaging with threads in the valve body, the threads between the cap and the valve body being of greater pitch than those between the cap and the valve stem.

In testimony whereof we hereunto affix our signatures.

CHARLES F. WALLACE.
MARTIN F. TIERNAN.
